UNITED STATES PATENT OFFICE.

JOSEPH E. McCRUDDEN, OF PROVIDENCE, RHODE ISLAND.

STOP FOR COUNTER-SHAFTS.

1,100,084.

Specification of Letters Patent. Patented June 16, 1914.

Application filed March 10, 1913. Serial No. 753,147.

To all whom it may concern:

Be it known that I, JOSEPH E. McCRUDDEN, a citizen of the United States, residing at Providence, in the county of Providence and State of Rhode Island, have invented 5 certain new and useful Improvements in Stops for Counter-Shafts, of which the following is a specification.

My invention relates as a new article of manufacture to a device or apparatus intended for the prevention of the accidental creeping of the belt from one pulley to another, and more particularly from a loose pulley to the fast pulley of a shafting where 10 creeping of the belt results in the unexpected actuation of the machine parts.

A further object is to effect the desired end by a structure that is simple, inexpensive and capable of application to any form 15 of shafting and which may be applied without any substantial re-organization of the shafting parts.

To the above ends essentially my invention consists in such parts and such combinations of parts as fall within the scope of 20 the appended claim.

In the accompanying drawings which form a part of this specification, Figure 1 is a front view of a shafting embodying my 25 invention, Fig. 2, a section on line $x-x$ of Fig. 1, Fig. 3, a side elevation of one of the clamping plates, Fig. 4, a section on line $y-y$ of Fig. 1, Figs. 5 and 6, top and side elevations respectively of the spring member, and 30 Fig. 7, a modified view of a hub.

Like reference characters indicate like parts throughout the views.

My invention is shown herein in connection with an ordinary shafting comprising 40 the usual hangers A, and hanger arms a carrying upon their ends the bearings a'.

B is the horizontal shaft mounted in the hangers in the usual manner, and C the shifter bar mounted in the bearings a' and 45 operated by the shifting lever D pivotally connected with the shifter bar at d, and operated in the usual manner.

E and E' are respectively the loose and fast pulleys, and e and e' the usual belt forks 50 therefor.

It is in conjunction with any well known shafting of which the above is a sample that my invention is herein shown. Integral with the shifter bar C or attached thereto in 55 any convenient manner is a hub F. This hub is located at either side of the hanger

that may be preferred. In the present instance it is illustrated outside one of the hangers. In detail it comprises a doubly inclined outer surface f, the inclination being 60 upwardly from the ends, forming a nearly elliptical body. Intermediate its length the hub is provided with a cavity g which may be of any desired shape, but preferably as shown V-shaped. The cavity may if desired be annular, as at g', in Fig. 7, without departing from the spirit of my invention. The hub F might be integral with the shifter rod C, but when non-integral with the bar the hub has a central axial opening G, as shown in Fig. 4, to receive the bar C and is provided with a threaded opening g² leading to the opening G to receive the shank h of a binding screw H adapted to bind the hub to the bar. One of 70 these hubs only is necessary for the purpose of my invention, but sometimes it is convenient to multiply the number of hubs, and as shown in Fig. 1 a second hub F' may be fixed to the shaft adjacent the first, but 75 more remote from the hanger. It will be understood that the hub F' is in all details similar to the hub described.

A spring member is adapted to register in the cavity g of the hub and retain the shifter 80 bar in shifted position. This spring J is provided with a depending substantially V-shaped head j upon its outer end, it being understood that the shape of this head or shoulder is governed largely by the cross 85 sectional shape of the cavity g and may be U-shaped in cross section without departing from the spirit of the invention. This spring is provided near the end opposite the head with a perforation j² to receive an attaching screw j³. It is highly advantageous 90 however to apply my device to a shafting already in position wherein it would be expensive or inconvenient or impossible to mount the parts without dismounting the 95 entire shafting already in position. In such cases an auxiliary portion of my invention consists in a device adapted to be applied to the shifter bar, which device affords a suitable member to which to fix the spring J. 100 In detail the auxiliary portion of the structure consists of two plates K and L, oblong in shape, and provided respectively with central openings k and l adapted to loosely receive the bar C, and provided respectively 105 with end openings k' and l' adapted to receive binding bolts M upon whose ends are 110

heads *m* bearing upon the outer face of the plate *L*, by means of which bolts and nuts the plates *K* and *L* are clamped rigidly against the ends of the cylindrical bearing 5 *a'*. The plate *K* is provided with a hub or boss *o* provided preferably with a flattened portion *o'* upon its side, which in the present instance is shown recessed to afford a support for the end of the spring *J* which is 10 attached to the hub *o* by the screw *j*³.

The operation of my device is as follows. When the shifting lever *D* is in the position shown in full lines in Fig. 1 the belt is on the loose pulley *E'*, and the spring 15 member *J* has its head in engagement in the cavity of the hub *F'*. When however the lever is thrown to the position shown in dotted lines whereby the belt is thrown upon the fast pulley *E* the head of the 20 spring member is thrown out of the cavity of the hub *F'* by reason of the longitudinal movement of the bar *C*, and the head engages in the cavity of the hub *F*. It will be understood that when only one hub is employed on the bar *C* that the spring head 25 will, after it has been unseated from its cavity, depend exteriorly of the hub since there will be no second hub to receive the head. The only difference being that 30 when two hubs are used the rod *C* is held rigidly both when the belt is upon the fast

pulley and when the belt is on the loose pulley. When only one hub is used the spring will engage the hub only when the belt is on one pulley. In the latter case it 35 is preferable that the pulley whereon the belt should be locked should be the loose pulley.

It will be observed that by the above described construction no accidental creeping 40 or other dislocation of the belt from the loose pulley to the fast pulley can take place.

What I claim is:—

In a shafting, the combination with a 45 bearing member and a shifter bar longitudinally movable therein, of a hub movable with said bar, a pair of plates bearing against the ends of said bearing member, one of said plates having a hub with flattened portion, means for securing the plates against the ends of the bearing member, and a resilient member secured at one end to the 50 said flattened portion and its free end engaging the hub on the shifter bar. 55

In testimony whereof I have affixed my signature in presence of two witnesses.

JOSEPH E. McCRUDDEN.
